UNITED STATES PATENT OFFICE.

JOHN B. WRIGHT AND FRANS O. LAWSON, OF GREENSBORO, NORTH CAROLINA,
ASSIGNORS TO WRIGHT SAFETY AIR-BRAKE COMPANY, OF GREENSBORO,
NORTH CAROLINA, A CORPORATION OF NORTH CAROLINA.

SAFETY RAILWAY-BRAKE.

1,352,861.

Specification of Letters Patent. Patented Sept. 14, 1920.

Application filed December 19, 1919. Serial No. 345,979.

To all whom it may concern:

Be it known that we, JOHN B. WRIGHT and FRANS O. LAWSON, citizens of the United States, residing at Greensboro, in the county of Guilford and State of North Carolina, have invented certain new and useful Improvements in Safety Railway-Brakes; and we do hereby declare the following to be a full, clear, and exact description of the same, 10 reference being had to the accompanying drawings, forming part of this specification.

This invention relates to brake mechanism for railway cars, etc., and more especially to mechanism designed for the purpose of applying the brakes in case of an abnormal displacement of the trucks with relation to the body of a car, such, for example, as would be occasioned by an abnormal movement of the body with relation to the trucks 20 caused, for instance, by high speed over a poor track, a partial or total derailment of the truck, "splitting a switch", or any one of the numerous conditions which are usually the remote or approximate cause of 25 a great majority of railway accidents.

Apparatus of the general type referred to is now in public use and is recognized by those familiar with the art as a product of the Wright Safety Air Brake Company, and 30 features of the appliances now in use are illustrated in the patents to Wright, No. 947,142, and No. 978,979, and in the patent to Wright & Lawson, No. 1,115,644, to which reference may be had for disclosure of features which may aid in an understanding of 35 the present invention.

One object of the present invention is to provide an improved means whereby abnormal displacement of the body of the car with 40 relation to the trucks or of the trucks with relation to the body may be made effective for operating a brake setting valve.

As in the prior devices of this character, the valve and one of the actuating members therefor, in the form of a pin, are carried on the car body and a second operating member is secured to the car truck. This second operating member completely surrounds or encircles the operating member 50 carried on the car body and with the devices as heretofore constructed it has been impossible to remove the car body from the

trucks without either removing the valve from the car body or the operating member from the truck, to avoid permanently damaging the valve and its actuating mechanism. 55 Another object of the present invention is to overcome this defect and to provide means whereby the car body may be intentionally removed from the trucks without removal or 60 injury of the valve mechanism, or otherwise destroying their operative relation when the truck and body are re-assembled.

Referring to the accompanying drawings: 65 Figure 1 is a fragmentary view illustrating one end of a car body with its truck more or less diagrammatically shown and with a brake controlling mechanism embodying the present invention.

Fig. 2 is a detail sectional view of the 70 valve mechanism and the operating mechanism therefor.

Fig. 3 is a detail view of the actuating pin.

Fig. 4 is a similar view of the operating 75 member which is mounted on the truck; and

Fig. 5 is a section in a vertical plane through the parts shown in Fig. 4.

A portion of the car body is indicated at A in Fig. 1 and the truck frame or bolster 80 at B, the truck frame being pivotally connected with the car body A in the usual manner. The usual appliances are provided for permitting of a limited relative movement of the truck frame and car body for 85 turning curves as well as the necessary or desirable spring action to relieve jars due to roughness of the track or roadbed.

The valve indicated at C in the drawings 90 may be any valve which, when actuated will bleed the train pipe so as to set the brakes, and in order that when once actuated it may be held in its actuating position, until manually closed or allowed to close, it is provided with a catch or locking device. The valve 95 adapted for illustrating the invention is one which corresponds closely with the valve commonly employed in safety railway brake equipment, as above referred to and embodies a casing D having an inwardly opening valve E. The casing D is secured to the car body adjacent the truck frame by hangers d, and is in communication with the train pipe of the brake system in such wise

that when the valve is opened, pressure is permitted to escape from the train pipe and the valve is held in its open position by a spring-pressed plunger F.

5 The plunger or catch is normally held retracted by engagement with a ring-shaped projection f on a slidable spool F' mounted in the casing at D intermediate to the valve E and an actuating member H to be pres-

10 ently described.

The actuating mechanism is of necessity located in proximity to one of the trucks of the car and it embodies as heretofore, a member or a pair of adjustable members G mounted on or rigidly, but adjustably, connected with the truck bolster B and having an aperture therein properly shaped to receive an actuating pin or member H for the valve E with sufficient clearance between the 20 pin H and the members G to permit of the desired normal relative movement between the truck bolster and the body of the car. The pin H is formed as a part of the mechanism which will be operated to effect the de- 25 sired movement of the valve, regardless of the direction in which the stem may be moved. As a convenient and preferred arrangement the pin H referred to projects from the periphery of a disk-like member K 30 horizontally through an opening in the valve casing which will permit the pin to swing through a very considerable arc in any direction. The periphery of the disk-like member has a circular projection K' on each 35 side and constitutes a pivot which is universal and the pin H and the disk-like member K jointly form a lever fulcrumed on a seat L in the bottom of the valve casing. A coöperating disk-like member M which oc- 40 cupies the space between the disk member K and the spool F' will, upon a movement of the operating pin H upward or downward from the horizontal plane in which it is normally positioned, be displaced up- 45 wardly as indicated in dotted lines and this movement is utilized for actuating the valve E controlling the bleeding of the train pipe for setting the brakes. The adjacent faces of the disk members K and M are pro- 50 vided at their center with a coöperating circular projection and recess which maintain the disk members in proper position.

To unseat the valve E upon a horizontal movement of the actuating pin H the seat L is provided with an elongated transverse recess 1, the side walls of which are inclined to form cam surfaces adapted to coöperate with the inclined side faces of an elongated projection N on the adjacent side of the 55 disk-like member K, of the actuating pin H. When the pin H is moved horizontally or laterally by abnormal relative movement of the truck and car body bringing the actuating member G on the truck in contact with 60 it, the cam faces formed by the side walls of

the recess and the projection on member K, will elevate the member K and move the valve E off of its seat. The pin and its head or disk-like end thus form a universal lever which will lift the valve when swung in any 70 direction.

The operating member G, held by brackets G' on the truck bolster, is preferably constructed of parts g, g', adjustable toward and away from each other so that the size of 75 the opening through which the operating pin H extends may be varied to permit of any desired degree of relative movement of the car body and truck frame without actuating the valve E. As heretofore men- 80 tioned, however, the operating members of the prior devices of this character are of such construction as to necessitate the detachment of the valve and pin H from the car body or the member G from the truck or 85 the damage of those parts when it is desired to raise the car body off of the trucks.

In the present invention this necessity of removal or damage of the valve or its actuating parts is eliminated by providing one 90 of the parts g of the operating member G with a slot S through which the actuating pin H may be passed when the car body is raised off of the trucks. To prevent the operating pin H passing through the slot S 95 without setting the brakes during abnormal relative vertical movements of the car body and truck when the train is in operation, the walls of said slot are angularly disposed with respect to the path in which the op- 100 erating member G travels during relative vertical movements of the truck and car body so that the pin H, when it comes in contact with one of the walls of the slot S, will be moved laterally or horizontally, thus 105 effecting the unseating of valve E as before described. The walls forming the entrance to the slot are preferably inclined to guide the pin into and out of the slot, whereby the car body may be jacked up and the truck 110 removed or replaced without danger of breaking the safety devices. It will be noted that the pin cannot pass through the slot without unseating the valve so that the efficiency of the device is not impaired. 115

What is claimed is:

1. In a derailment control mechanism for railway brakes, the combination of the valve carried on the car body, an actuating member therefor movable laterally and vertically in any direction by relative abnormal movements of the car body and truck to unseat said valve, a bearing member for said actuating member, coöperating cam surfaces on the actuating and bearing mem- 120 bers adapted to move the actuating member away from the bearing member in a direc- 125 tion at substantially right angles to the face of the bearing member to unseat the valve upon relative abnormal movements of the 130

truck and car body, and a second operating member carried by the truck adapted to operate said actuating member.

2. In a derailment control mechanism for railway brakes, the combination of the valve carried on the car body, an actuating member therefor movable laterally and vertically in any direction by relative abnormal movements of the car body and truck to unseat said valve, a bearing member for said actuating member, coöperating cam surfaces on the actuating and bearing members adapted to move the actuating member away from the bearing member in a direction at substantially right angles to the face of the bearing member to unseat the valve upon relative abnormal movements of the truck and car body, and a second operating member carried by the truck and loosely encircling the first-mentioned actuating member and adapted to operate said actuating member.

3. In a derailment control mechanism for railway brakes, the combination of the valve carried on the car body, an actuator therefor movable laterally and vertically in any direction to open the valve, and an operating member carried by the truck encircling the actuating member and adapted to operate said actuating member, and means formed in the operating member on the truck for permitting removal of the actuating member from within the same in a vertical plane.

35 4. In a derailment control mechanism for railway brakes, the combination of the valve carried on the car body, an actuating member therefor movable laterally and vertically in any direction by relative abnormal movements of the car body and truck to unseat said valve, a bearing member for said actuating member, coöperating cam surfaces on the actuating and bearing members whereby the valve will be unseated by relative abnormal movements of the truck and car body, and a second operating member carried by the truck and loosely encircling the first-mentioned actuating member and adapted to operate said actuating member, the operating member on the truck having a slot formed therein for removal of the actuating member, and the walls of said slot being angularly disposed with respect to the path in which the operating member on the truck travels during abnormal relative ver-

tical movements whereby passage of the actuating member through said slot will unseat the valve.

5. In a derailment controlling mechanism for railway brakes the combination of the valve casing carried on the car body, a bearing seat in the valve casing, an actuating member for the valve pivoted near one end on the bearing seat and movable universally on an axis within the bearing seat, means for unseating the valve when the actuating member is moved above or below the horizontal, coöperating cam surfaces on the bearing seat and actuating member for unseating the valve when the actuating member is moved laterally, and a second operating member carried by the truck for effecting movements of the actuating member upon relative abnormal movements of the car body and truck.

6. In a derailment controlling mechanism for railway brakes, the combination with the valve carried on the car body, a bearing seat having an elongated recess in one of its faces, an actuating member for the valve movable vertically or laterally in any direction to open the valve, said actuating member having an enlarged end, an elongated projection on the enlarged end of the actuating member normally seated in the recess in the bearing seat, and adapted to force the valve off of its seat when moved out of said recess in the bearing seat, and a second operating member carried by the truck adapted to operate the first mentioned actuating member upon relative abnormal vertical or lateral movement of the car truck and body.

7. In a derailment controlling mechanism for railway brakes, the combination of the valve carried on the car body, an actuator therefor movable laterally in any direction and vertically to open the valve, and an operating member carried by the truck encircling the actuating member, said operating member on the truck having a slot formed therein for the removal of the actuator and the walls of said slot being disposed at an angle to the path in which the operating member on the truck travels during relative vertical movements whereby passage of the actuator through the slot will unseat the valve.
